(57) CLAIM

I claim the ornamental design for the towel dispenser, as shown and described.

DESCRIPTION

FIG. 1 is a perspective view taken from the front and top of the towel dispenser of my design shown with a roll of disposable towels in the container and a portion of the disposable towel extending through the top of the dispenser; FIG. 2 is a front view of the towel dispenser of my design, the opposite side being a mirror image;

FIG. 3 is a left side view thereof;

FIG. 4 is a right side view thereof;

FIG. 5 is a top view thereof;

FIG. 6 is a bottom view thereof;

FIG. 7 is a perspective view taken from the top and front of an alternative embodiment of the towel dispenser shown with a roll of disposable towels in the container and a portion of the disposable towel extending through the top of the dispenser;

FIG. 8 is a front view of the alternate embodiment of the towel dispenser;

FIG. 9 is a left side view thereof;

FIG. 10 is a right side view thereof;

FIG. 11 is a top view thereof; and,

FIG. 12 is a bottom view thereof.

Where included, broken lines showing environment or structure are for illustrative purposes only and form no part of the claimed design.
